BOTTLE

Bruce L. Roberts, Rossford, Ohio, assignor to Owens-Illinois Glass Company, Toledo, Ohio, a corporation of Ohio

Filed Dec. 9, 1964, Ser. No. 82,963

Term of patent 14 years

(Cl. D58—6)

FIG. 1

FIG. 2

The back and the side not shown are the same as those shown. The characteristic features of this design reside in the configuration shown in full lines on the drawing.

I claim:

The ornamental design for a bottle, substantially as shown and described.
